United States Patent Office

Des. 185,076
Patented May 5, 1959

185,076

TOASTER

Robert O. Ernest, Oak Park, and Ross E. Cornwell, Chicago, Ill., assignors to Sunbeam Corporation, Chicago, Ill., a corporation of Illinois

Application April 18, 1958, Serial No. 50,513

Term of patent 14 years

(Cl. D81—10)

FIG. 1.

FIG. 2.

Fig. 1 is a perspective view of a toaster embodying our new design;

Fig. 2 is a side elevational view of the toaster shown in Fig. 1;

Fig. 3 is a top plan view thereof;

Fig. 4 is an end elevational view of the toaster taken from the right of Fig. 2; and

Fig. 5 is an end elevational view thereof taken from the left of Fig. 2.

We claim:

The ornamental design for a toaster, as shown.
